UNITED STATES PATENT OFFICE

2,005,229

VAPORIZER

Clarence J. Loos and Louis J. Miller, Chicago, Ill.

Application January 29, 1932, Serial No. 589,580

5 Claims. (Cl. 128—192)

This invention has to do with vaporizers and more particularly with an improved type of vaporizer adapted to be attached to the body of the user.

5 To and including the present time, vaporizers have been of a crude and inconvenient form. Especially has this been true when vaporizing treatment has been desired for infants or adult persons confined to the bed because of the excess weight which makes the conventional vaporizer unwieldy, and because the structure thereof did not lend itself to use with such patients.

It is an object of the present invention to provide a vaporizer light in weight with means for attaching it in a suitable manner to a patient.

15 Another object of the present invention is to provide a vaporizer that when supported on the person of the patient by the means provided, it will, regardless of the position of the patient, maintain the vessel containing the material being vaporized in an upright position.

Still another object of the present invention is to provide a new and improved form of cup for a vaporant.

20 Another object of the present invention is to provide as complemental to a vaporizer a hood adapted to direct the fumes arising therefrom toward the face of a patient.

Another object of the present invention is to provide in a vaporizer pivotal or other supports for the housing rotated ninety degrees from other pivotal or similar supports for the vaporant cup carried therein, that the cup may differentially retain its equilibrium.

30 Further objects and advantages of this invention and the details of its construction will be fully understood from the following description and accompanying drawing where like reference numerals relate to similar parts and in which;

40 Figure 1 shows in perspective an elevation of the embodiment of the invention;

Figure 2 is an orthographic projection of the invention with a fragment thereof in cross section, and taken at ninety degrees to Figure 1;

45 Figure 3 is a fragmentary sectional view of the invention taken along the line 3—3, Figure 2; and

Figure 4 is a fragmentary view illustrating a portion of the invention in detail.

The reference character 10 indicates a housing for the device and around which the remainder of the apparatus is constructed (see Figure 2). Said housing 10 has a flat circular bottom 11 and an oblate spheroid side wall 12 rising from the circumference thereof; the whole being of sheet material, either a metal or a dielectric.

Oppositely disposed in the upper section of walls 12 are two apertures 13. Within these apertures 13 are seated bushing members 14 which carry in a pivotal manner the inner mechanism of the device. Said bushing members comprise an outer casing 15 of a dielectric material. Within the casing 15 is disposed a bearing member 16 having therein an axial recess 17. A head 18 composing the outer end of the bearing proper is entirely enveloped by the pocket 19 at the outer 10 end of the casing and to prevent longitudinal movement relative the bearing and the casing.

Surrounding the inner extension of the casing 15 is an insulating washer 21 and adjacent the wall 12 to measurably position a metal lug 22 15 from the wall. The lug 22 is in electrical contact with the bearing member 16 and the selected assembly therewith is retained by a nut 23 engaging the threads at the extreme inner end of the bearing member.

20 Diametrically opposed trunnions 24 are disposed within the recess 17 and support a compound ring 24a which is composed of an outer and inner member designated by numbers 25 and 26 respectively. These rings 25 and 26 hold 25 securely therebetween electrical conductor strips 27. Within the inner ring 25 will be noted apertures 28 which register with heads 29 terminating the inner end of trunnions 24. The cut away section 28 provides that the trunnion 24 will draw 30 said head in electrical contact with the conductor strip 27 when the nut 30 is tightened upon threads 31.

35 Located at ninety degrees from the above described trunnions and within the rings 25 and 28 are bushings 32. The outer ring 26 contains an aperture 33 on a common axis with a smaller aperture 34 in the inner ring 25. In registry to and intermediate apertures 33 and 34 is a third aperture 35 within the electrical conductor strip 27, said aperture being of the same diameter as aperture 34. Therefore, when the bushing 32 is costated within the three mentioned apertures the larger aperture 33 receives the enlarged portion 36 of the bushing, that said portion will come in contact with the conductor strip 27, while the journal portion 37 of said bushing extends into the other two apertures and somewhat beyond the inner edge of the ring 25 where a nut 38 is screwed thereon to secure the assembly, and draw the enlarged portion of the bushing in close contact with the conductor strip. A metal basin 39 is centrally located within the ring 24a and is pivotally suspended therefrom by the engagement of trunnions 40 within the 55

bushing 32. A flange 41 at the upper periphery of the basin 39 presents holes 42 in registry with others in the broadened end 43 of trunnions 40, whereby connection therebetween is provided by rivets 44.

5 In the bottom of basin 39 is a large circular aperture 45 circumscribed by a shoulder 46. A 10 block 47 made of porcelain or other heat-resisting material is seated within opening 45 and is 15 supported therein by lugs 48, spaced at equal intervals to project radially from the top wall 49. The upper face of block 47 has a centrally located circular recess 50 having a flat bottom 51, from which project upwardly a plurality of parallel ribs 52.

15 An electrical heating element 53 is progressively 20 and undulatingly wound about ribs 52 to lie on bottom 51 and have its two ends disposed at 54. Directly opposite 54 in the wall 49 of the block 25 are openings 55 providing communication from the recess 50 within said block to the outside.

25 Resting upon the top wall 49 of the block is a 30 vaporizer pan 56 open at the top and presenting side walls 57 in juxtaposition to those of the basin 39. The side walls 57 of pan 56 are corrugated to incorporate therein vertical ribs 58 as shown in cross section in Figure 3.

30 Contiguous to the outer surface of basin 39 and intermediate said surface and an electrical 35 conductor 59 is a flat strip of insulating material 60. The electrical conductors 59 lead from either end 54 of electric heating element 53 to be anchored under the head at the lower end of bolts or rivets 44. Thus the insulating material 40 45 insures that no short-circuit will occur by these conductors coming into contact with the basin 39. Also, it will be observed that holes 61 in the flange 41 of the basin 39 are considerably larger than the shanks of the bolts 44 and an insulating washer 62 separates the flange 41 and trunnions 40 to insure that said basin will not 50 contact the bolts or trunnions which are electrically connected to conductors 59.

45 From the trunnions 40 and away from the heating element 53 the electric circuit leads by way of conductor strips 21, within the ring 24a, to trunnions 24, thence to metal clips 22. To the members 22 are soldered an end of flexible electric leads 63, the latter carrying well down under the swinging posts of the device and adjacent the walls 12 anterior to contributing to a duplex conductor member 64 and leading without the housing by way of an eyelet 65. From eyelet 65 conductor 64 progresses to terminate in an ordinary lighting plug to adapt the device to any convenient electric source. A snap switch may be placed in this cord to more easily facilitate turning "on" and "off" the electric source.

60 Seated upon the housing 10 is a hood 66 of a peculiar shape, comprising a circular shoulder 67, to extend upward and diminishing in diameter to form a neck 68, extending still upwardly and increasing in diameter to form a head 69. The hood 66 is hollow and constructed of the same material as housing 10. An angular opening 70 is provided in the head of the hood 66 and on the opposite side of the device to eyelet 65 of housing 10. The lower rim of the hood has arcuate cutaway sections 71 to provide space for insulating sleeves 15 and to register therewith. The hood shoulder 67 telescopes rather tightly over the top edge of the housing to thus insure correct position when once assumed.

75 Projections or knobs 72 may be formed intricate the exposed ends of insulating caps 15 to

provide means of attaching cords or straps 73 as one form of support for the device. Cords 73 may be joined at the free ends or arranged in some other suitable manner to fasten the device to the head or shoulders of a patient.

5 During the heating of a vaporant in the device, heat is radiated from unit 53 at the bottom of the vaporizer pan, and is carried by convection upwardly along the corrugations in the side walls thereof, where more wall surface is exposed to the heated air by the presence of such corrugations. Hence, the period of time necessary to vaporize the vaporant is decreased. The vapor is carried by convection upwardly through the hood to be directed outward of the opening 15 20 toward the nostrils of the patient.

25 The device, if attached to a person, is so arranged that the angular opening 70 will be next to the patient and eyelet 65 with the electric conductors passing therethrough will be on the 20 opposite side of said device from him. When it is not desired to attach the device to a person, ample area is provided by flat base 11 to insure an upright position when the device is resting on a flat surface.

30 Since the center of mass of the parts associated within the ring 24a depends below both the rotating axes there contained, angular displacement of the housing to the horizontal in any direction will not tilt the vaporant cup. For example, when trunnions 24 are at different elevations, the cup and heating element will swing within bushings 32 to maintain a horizontal state. When the housing assumes an askance position 35 40 45 50 55 60 65 70 75 80 85 90 degrees from the above illustrated position, the weight of the cup and porcelain block will rotate the ring 24a within bearing members 16. Any angular displacement of the housing intermediate the two special cases recited will result in complementary rotation of the swinging elements about the differential axes whereby the vaporant cup retains its upright position that no hot and liquid vaporant will be spilled therefrom.

55 We claim:

1. A vaporizer device comprising a housing, a pan movably disposed therein, and a heating element movable with said pan and a hood removably connected to said housing and extending below the plane of the top of said pan.

2. A vaporizer device comprising a housing having an opening in the top, there being a pan, and a heating element for said pan in said housing and movable therein, and a hollow hood having an opening at either end, said hood being removably attached to said housing in a plane below the normal level of the top of said pan so that the vapors from said pan normally are released above the level of the connection between said housing and said hood.

3. In a vaporizer device, the combination of a housing having walls, bearings diametrically opposite in said walls, a ring rotatively mounted on said bearings, an axis in said ring normal to that determined by said diametric bearings, a basin depending from said axis, a heating element supported by said basin, and a vaporant pan above said heating unit, and in which combination said elements are in close connection with the center of mass below the plane of said ring.

4. In a vaporizer, a housing, a dielectric ring mounted in said housing and comprising an inner element and an outer element, and electrical

conducting means intermediate said inner element and said outer element.

5. A vaporizer device comprising a receptacle having therein a support member provided with a heating element, a gimbal joint connecting means between said heating element and said receptacle, there being upon and wholly above said heating element a pan for holding a vaporizer material, conductor means from a source 10 of energy and extending through said receptacle

and including said gimbal joint providing a circuit to said heating element, and a removable hood having an axis coincident with the axes of said base and pan when the latter are in normal position and comprising a slip over section having its lower edge well below the top level of said pan.
